(57) **CLAIM**

The ornamental design for a packaging bag, as shown and described.

DESCRIPTION

FIG. 1 is a front elevational view of the first embodiment the packaging bag showing my new design;

FIG. 2 is a top plan view thereof;

FIG. 3 is a rear elevational view thereof;

FIG. 4 is a bottom plan view thereof;

FIG. 5 is a right-side elevational view thereof; and

FIG. 6 is a reference view showing the packing bag in a filled state.

FIG. 7 is a front elevational view of the second embodiment the packaging bag;

FIG. 8 is a top plan view thereof;

FIG. 9 is a rear elevational view thereof;

FIG. 10 is a bottom plan view thereof;

FIG. 11 is a right-side elevational view thereof; and,

FIG. 12 is a reference view showing the packing bag in a filled state.

The broken lines depict portions of the packaging bag that form no part of the claimed design.
